ELECTRIC OUTLET BOX COVER PLATE

Earl E. Smith, Charlevoix, Mich., assignor to Lexalite
Corporation, Charlevoix, Mich.

Filed Mar. 30, 1970, Ser. No. 22,117

Term of patent 14 years

Int. Cl. D13—03

U.S. Cl. D26—13

FIG. 1

FIG. 2

FIG. 3

FIG. 4

FIG. 5

FIG. 6

FIG. 7

FIG. 8

FIG. 1 is a front perspective view of an electric outlet box cover plate embodying my new design;

FIG. 2 is a rear perspective view of the cover plate;

FIG. 3 is a right-hand side elevational view of the cover plate;

FIG. 4 is a bottom view of the cover plate;

FIG. 5 is a front perspective view of another electric outlet box cover plate embodying my new design;

FIG. 6 is a rear perspective view of the cover plate of FIG. 5;

FIG. 7 is a right-hand side elevational view of the cover plate of FIG. 5; and

FIG. 8 is a bottom view of the cover plate of FIG. 5.

The left-hand side elevational views are mirror images of the right-hand side elevational views shown, and the top views are mirror images of the bottom views

I claim:

The ornamental design for an electric outlet box cover plate, substantially as shown and described.
